UNITED STATES PATENT OFFICE

HARRY H. VICKERS, OF ST. ALBANS, NEW YORK, ASSIGNOR TO UNDERWOOD ELLIOTT FISHER COMPANY, OF NEW YORK, N. Y., A CORPORATION OF DELAWARE

TYPEWRITING MACHINE

Original application filed June 9, 1925, Serial No. 35,858, now Patent No. 1,743,640, dated January 14, 1930.
Divided and this application filed September 13, 1929, Serial No. 392,295.

This invention relates to work-sheet-handling devices for typewriting machines, and is herein illustrated as applied to an Underwood combined typewriting and computing machine of the Underwood-Hanson type.

According to this invention, the amounts written on different varieties of checks are accumulated on different registers of the computing mechanism, each kind of check having its associated register, the checks being selectively positioned on the carriage, and the carriage being shifted to a corresponding position preparatory to accumulating the amount in the corresponding register. In this way checks upon different banks may be typed expeditiously, and correct accounting is insured for each bank or drawee.

In order to expedite the positioning of the checks relatively to the registers, there is provided an aligning or collating plate or table slidably mounted upon a shaft fast to the platen-frame, the plate being provided with mechanism whereby it may be accurately positioned and locked in any one of a plurality of column positions, each column position corresponding with the position of one of the registers of the machine.

A pack or assemblage of work-sheets may comprise a string or strip of checks joined serially and a record-sheet, the two sheets being interleaved by a carbon, and both the record and the carbon sheets being wider than the checks. This assemblage is inserted at the rear of the typewriting machine, leading edge first, over a rear paper-chute, passing under the platen, and with the aid of the feed-rolls is fed around and up past the printing point. The record-sheet is then led under the side pressure-rolls at the top of the platen and behind the collating plate, the checks being positioned between upturned edges of the plate. A line is then typed upon the first or upper check, and is duplicated upon the record-sheet by means of the carbon. The platen is line-spaced and the carriage returned, preparatory to repositioning the checks, to present a fresh check to the printing line, thus keeping the typed data on the record-sheet in a condensed form.

The feed-rolls are released to free the checks, which are then pulled upwardly for positioning the next check relatively to the printing line, said position being gaged by the aid of the wing-scales of the machine. 55 It will be understood that while the feed-rolls are released to raise the checks, the record and the carbon sheets are held upon the platen, against accidental displacement, by means of the pressure-rolls which hold 60 the edges of the record and carbon sheets. The feed-rolls are again restored, and the corresponding tabulator-key is depressed to move the carriage in registering position with the totalizer, whereupon a new line 65 65 may be typed upon the second check, and the cycle of operations is repeated.

When it is desired to type another class of checks, that is to say, checks chargeable to another account, the aligning, locating or 70 collating plate is shifted to a column-position corresponding to the column-position of the register in which it is desired to accumulate the amount. In order to shift the plate, however, it is first necessary to release a positioning and locking latch preparatory to 75 shifting the plate for another column-position, in which position the plate is automatically locked, by means provided for the latch.

In some classes of work a record-sheet 80 is used upon which numbers corresponding to the numbers of the checks are printed thereon, previous to their being inserted in the machine. In order that the number on the record-sheet may be visible outside the 85 margin of the check, the record-sheet is provided with an extra wide margin in one of the sides, upon which margin the number is printed and is used as a reference or check against the number on the check. In other 90 classes of work, however, the record-sheet is blank and the number is only printed on the check, the number being typed upon the record-sheet through the carbon by typing it upon the check. In order that the device 95 may be used alternatively for either class of work, there is provided mechanism whereby the pressure-rolls may be adjusted to take either a wide or a narrow record-sheet.

This is a division of my application Se- 100

rial No. 35,858, filed June 9, 1925. (Now Patent No. 1,743,640, dated January 14, 1930.)

Other features and advantages will hereinafter appear.

5 In the accompanying drawing,

Figure 1 is a front view, in elevation, of the aligning table as applied to an Underwood combined typewriting and computing machine.

10 Figure 2 is a cross-sectional view, in elevation, through the line 2—2 of Figure 1, looking in the direction of the arrows, and shows both the typewriting and the computing mechanism.

15 Figure 3 is a plan view of a detail showing the table-frame and the indexing mechanism therefor.

20 Figure 4 is a plan view of the table and the pressure-rolls adjusted for a wide record-sheet.

Figure 5 is a front view, in elevation, of the table showing the check and a wide record-sheet.

25 Figure 6 is a detail showing the table-locking mechanism in its operated position.

30 Figure 7 is a diagrammatic plan view of the machine, illustrating how the table can be used to position checks relative to the denominational selectors of the computing mechanism.

35 This invention is herein illustrated as applied to a combined typewriting and computing machine of the Underwood-Hanson type in which the computing mechanism is indicated by the numeral 10.

40 It is proposed to insert an assembled pack or work-sheet 11 at the rear of the machine, down a rear chute or table 12 under a platen 13, co-operating with feed-rolls 14, and up 45 in front of the platen, past the printing point. The work-sheet comprises a string of duplicate checks or forms 15 joined together and a record-sheet 16, the two being interleaved by a sheet of carbon. The record-sheet and 50 the carbon are wider than the check forms at the sides thereof, the record and the carbon sheets being led behind a front table, locator or plate 17, and the borders thereof are held under pressure over the platen by means of 55 pressure-rolls 18. The checks are led over the front table and are positioned by squaring the sides thereof against upturned edges 19 of the table 17.

60 A line of typing is written upon the check by swinging type-bars 20 and then the work-sheet is line-spaced by means of the line-spacing mechanism 21, preparatory to repositioning the forms. The feed-rolls 14 are released in order to permit the moving of the 65 forms upwardly so as to present a fresh form to the printing line.

65 When it is desired to type another string of forms and to accumulate the amounts in a different register or to manifold the 70 amounts in a different column on the record-

sheet, the aligning plate is shifted to a position co-operating with the register or a record column in which it is desired to compute or type the amount, and, for this purpose, the table is slidably mounted on a cross-rod 22, fast to the end plates 23 of the platen-frame by means of screws 24. The rod is provided with a longitudinal groove 25 for receiving rollers 26 which are pressed against said rod by springs 27. Said rollers are mounted in slots 28 between the sides 29 of brackets 30, the brackets being provided with forwardly-extending arms 31 and 32, the ends thereof being bent at 33 for receiving a cross-bar 34 fast to the arm 32, by means of screws 35, which also serve as a means for supporting the guide-fingers 36 upon which the pressure-rolls are rotatably mounted. The aligning plate 17 is adjustably mounted upon the cross-bar 34 by means of screws 37 through slots 37^a in the plate, the slots being countersunk to receive the heads of the screws so as to present a flat surface to the work-sheet.

70 In order to shift the aligning plate to a different position, a latch 38 is swung on a pivot-stud 39 against the tension of a spring 40 by depressing a finger-piece 41, so as to swing the latch from a position shown in Figure 2 to that shown in Figure 6. The latch is provided with an open slot 42 at the end thereof, the slot controlling the swing of the latch, which engages in its normal position with indentations 43, cut in the cross-rod 22, the spacing and position of the cuts corresponding to the column-positions of tabulating stops 44, which, in turn, correspond to the setting of the registers in the computing mechanism. In order to facilitate the sliding of the aligning plate on the rod 22, there is provided a finger-piece 45 which may form 75 an integral part of the forwardly-extending arm 31.

80 In Figure 7 is illustrated the relative position of certain parts of the computing mechanism when the right-hand portion of a check that is disposed on the table 17 is brought to the printing point of the machine for having the numerical amount of the check typed and computed. It can be seen that when the latch 38 of the table 17 is set in the first notch 43, and the usual right-hand portion of the check is brought to the printing point, a dog 10^d of the computing mechanism engages 85 a member of the first group of denominational selectors 10^s, which group corresponds to and controls in the usual way the first one from the right of a plurality of computing registers 10^r. Thus the numerical amounts of the checks typed while the table 17 is gaged by the first notch 43 (from the left) will be manifolded in the first column on the record-sheet and computed in the first register 10^r (from the right). In like manner, the checks typed while the table is gaged by 90 the second notch will be manifolded in the 95 100 105 110 115 120 125 130

second column and computed in the second register, and so on.

In some classes of work there is provided a plain record-sheet, as shown in Figure 1, and the number of the check is copied upon the check and is transferred upon the record-sheet through the carbon, the number being stamped upon the check by means of a numbering machine. In some other classes of work, however, the record-sheet is stamped with numbers corresponding to the numbers on the checks, and, in such cases, it is desirable that the number on the record-sheet be seen outside of the margin of the check, so as to facilitate the aligning of the checks with the corresponding numbers on the record-sheet. In order that the same device may be used in connection with both classes of work, there is provided mechanism whereby the frame supporting the aligning plate may be widened as shown in Figure 5 to thus move the right-hand pressure-roll outwardly to take a wider record-sheet upon which the numbers 46 of the checks are printed, the corresponding number on the checks being indicated by the numeral 47. In order to facilitate the positioning of the pressure-roll relatively to the aligning plate, the cross-bar 34 is provided with a slot 48 for receiving a threaded finger-piece 49 which screws into a tapped hole in the bent portion 33 of the arm 31. The adjustment of the pressure-roll is limited by a pair of collars 50 settable mounted on a rod 51, the rod being controlled by a pair of collars 52 at the end thereof.

It will be understood that the aligning table is mounted upon a rod 22, which is substituted for the regular pressure-roll-shaft of the machine, and that due to the resilient nature of the rollers 26, which engage with the groove in the rod, the table may be swung rearwardly as shown in dot-and-dash lines in Figure 2, in case it is desired to use the machine for ordinary typewriting. It will also be understood that the aligning plate is controlled between the range of the registers by means of collars 53 settable upon the rod 22.

The operation of the improved machine, particularly that relating to the selective engagement of the dog 10^a (Figure 7) with the groups of denomination-selectors, is as follows:

Assuming that there are, say, five groups of checks drawn on five different banks, which checks are to be filled out on the typewriter and the amounts thereof are to be accumulated or totaled in the five separate registers, and assuming, for the sake of simplicity, that checks drawn on bank No. 1 are to be filled out first, the collating paper-table 17 is shifted until its latch engages the first notch from the left on the bar 22 (notch marked "1" in Figure 7). The check is then located on the platen and collating table

(or it may previously have been located) and the carriage moved to the right, and the dog is then set on the rear of the carriage in such a position that when the amount for which the check is drawn is typed in numbers in the number space on the check (i. e., the "\$—" space), the dog will engage the first group of denomination trains from the right (i. e., selector-jacks), thereby actuating the computing mechanism of the first register. When the first check No. 1 is completed, it is withdrawn as described hereinbefore, another check No. 1 inserted, the carriage moved to the right and the typing begun again and repeated until all the checks No. 1 have been typed and computed.

When it is desired to type checks drawn on bank No. 2, the table is shifted until latch 38 engages the second notch or indentation 43 from the left. The dog, however, is not moved, but remains in its original position throughout all the operations on all the checks. Since the table has been shifted to the right on the carriage, and since the dog is fixed on the carriage, the dog has, relatively to the table, shifted to the left a distance equal to that between two notches or indentations 43, i. e., the distance between centers of adjacent groups of denomination trains 10^a (Figure 7).

(The tabulating stops 44, which are spaced apart the same distance as the notches 43, assist the operator in locating the point on the check at which numerals should be begun to be typed, although where standard forms of checks are used, the "\$" sign on the check may be a sufficient guide without the aid of the stop.) The dog will therefore engage the second group of denomination trains (selector-jacks) when the numerals on check No. 2 are typed. In the same way, the other corresponding groups of denomination trains or selectors will be engaged by the dog after the table has been shifted to cause the latch 38 to engage in any one of the notches. This collating table, with its shiftable frame, therefore, in addition to its function of positioning and supporting the checks, is also a means for selectively determining in which one of a record-sheet column or which one of the plurality of registers the amount typed upon any check, or upon any form, for that matter, shall be accumulated.

While this invention has been described as used with checks of standard form, it is apparent that it may be used with non-uniform forms, provided only the forms are so positioned on the platen and table that their effective printing line or numeral line or column comes into registry with the proper tabulating stop at the proper time. These tabulating stops may be dispensed with if care is taken, after the dog has once been set, all ways to locate the numeral line or column in

exactly the same position on the table where irregular forms are used. It is clear that the tabulating stops may be used alone to so locate the dog that it will engage the desired train group at the proper time, although this method will require careful positioning of the work-sheet.

It will therefore be obvious that once the dog has been set, no further manipulation of the dog is necessary. In view of the fact that the dog is located on the rear of the carriage out of sight of the operator, the setting of the dog, in the known type of machine, for every kind of check or form typed, to engage the appropriate group of denomination trains, demands that the operator get up from his seat to obtain a good view of the rear part of the machine. Moreover, the setting of the dog requires great skill and care and considerable time. All these expenditures of time, skill and effort are avoided by the use of the present invention in which, after the dog has once been set, the operator can make all subsequent selections of the appropriate register and record-column by simply shifting the collating table, which requires no more effort than line-spacing the platen. The mechanism for effecting such column-selection upon the record-sheet, it will be apparent, is within convenient reach of the operator.

Variations may be resorted to within the scope of the invention, and portions of the improvements may be used without others.

Having thus described my invention, I claim:

1. In a typewriting and computing machine, the combination with a carriage, a cross-rod fastened in the ends of said carriage, and a collating table mounted on said cross-rod for lateral adjustment with respect to said carriage, of means for readily latching said table in a plurality of positions on said rod, said means including a finger-piece pivoted above said cross-rod, and having a substantially flat tab-portion extending forwardly from said cross-rod, and a portion having an open slot extending downwardly from the pivot to straddle said cross-rod, and a spring normally pressing said slotted portion against said cross-rod for engaging in notches cut in the back of said cross-rod, the construction of said finger-piece and said spring being such that, when said table is moved from one notch along the rod, said slotted portion slides on the cross-rod and snaps into the next notch without attention from the operative.

2. In a device of the class described, the combination with a carriage, a platen, and a cross-rod fastened in the ends of said carriage behind said platen, of a frame including two forwardly-extending arms fastened to said rod to be moved laterally therealong, a bar rigidly fastened to the forward end of the

left-hand arm and adjustably fastened to the forward end of the right-hand arm, so that the right-hand arm may be moved laterally with respect to the left-hand arm, a second rod disposed between said bar and said cross-rod and having one end rigidly fastened to said left-hand arm and its other end arranged for extending through a closely fitting hole in the right-hand arm, and two collars on said second rod fastened so as to limit the movement of said right-hand arm with respect to said left-hand arm, said last-named rod also serving to help brace said frame upon movement of the same.

3. In a device of the class described, the combination with a platen and a platen-frame, of a notched cross-rod extending lengthwise of the platen and fastened in the ends of said platen-frame, a laterally-movable work-piece-aligning plate mounted on said rod, and an instrumentality for latching said plate in a plurality of positions along said rod, said instrumentality including a spring-actuated finger-piece pivoted above said cross-rod and having a depending piece disposed for engaging in the notches of said rod.

4. In a device of the class described, the combination with a platen and a platen-frame, of a tie-rod extending parallel with the platen and secured to the ends of the platen-frame, notches in said rod, each notch to indicate a column-zone along the platen, a carrier slidably mounted upon said rod, a sheet-aligning plate secured to said carrier, a pair of paper-fingers secured to said carrier, one paper-finger at each side of the aligning plate to bear upon the platen, and a latch pivotally mounted upon said carrier to engage said notches to locate the carrier and paper-fingers along the platen, said latch formed with a pair of extensions to straddle the rod and limit the swing of the latch in two directions, said latch also having a spring tensioned in a notch-interlocking direction and released from a notch by a finger-pressure during the shifting of the aligning plate along the rod.

5. In a device of the class described, the combination with a platen and a platen-frame, of a notched cross-rod extending lengthwise of the platen in the rear of the same to be fastened in the ends of said platen-frame, a laterally-movable frame mounted on said cross-rod and extending forwardly over said platen, a work-piece-aligning plate fast on said movable frame, a roll mounted on said movable frame at each side of said aligning plate, and means for pressing said movable frame toward the platen, whereby said rolls may securely hold on said platen an underlying work-sheet that is wider than the work-sheet disposed on said aligning plate, the right-hand one of said rolls being mounted on said movable frame for lateral adjustment.

with respect to said aligning plate, whereby the width of said underlying work-sheet may be varied.

6. In a device of the class described, the combination with a platen, a platen-frame and a cross-rod extending lengthwise of the platen in the rear of the same, of a laterally-movable frame mounted on said cross-rod and including two end pieces which are fastened to said cross-rod for adjustment laterally and extend forwardly therefrom and having their front ends bent inwardly at substantially right angles, a platen-engaging roll fastened on each of said bent ends for engaging a work-sheet passing under said movable frame, said movable frame further including a bar extending between said ends and being rigidly fastened to the bent portion of the left-hand end piece, said bar being provided with a slot at its right end, a thumb-screw passing through said slot and being threaded into the bent portion of the right-hand end piece, whereby the distance between said rolls may be varied, and an aligning piece mounted on said cross-rod between said rolls and upon which a second work-sheet may be disposed.

7. In a device of the class described, the combination with a platen and a platen-frame, of a tie-rod extending parallel with the platen and secured to the ends of the platen-frame, notches in said rod, each notch to indicate a column-zone along the platen, a carrier slidably mounted upon said rod, a sheet-aligning plate secured to said carrier, a pair of paper-fingers secured to said carrier, one paper-finger at each side of the aligning plate to bear upon the platen, and a latch pivotally mounted upon said carrier to engage said notches to locate the carrier and paper-fingers along the platen, said latch formed with a pair of extensions to straddle the rod and limit the swing of the latch in two directions.
